Melvin R. Warren,
INVENTOR

BY Victor J. Evans

ATTORNEY

WITNESS: *Bobbickey*

UNITED STATES PATENT OFFICE

MELVIN R. WARREN, OF MICHIGAN CITY, INDIANA

RADIATOR SCREEN

Application filed April 6, 1928. Serial No. 267,951.

This invention relates to straining means for the water in the cooling system of a motor vehicle, the general object of the invention being to provide means for straining the water as it passes from the jacket of the motor to the radiator so as to prevent foreign matter in the water from clogging the radiator.

Another object of the invention is to so form the screening device that it can be easily and quickly put in place and to provide means for cleaning the screening medium whenever necessary.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a view showing portion of a motor and a radiator, with the invention located in the line which connects the water jacket of the motor with the radiator.

Figure 2 is a sectional view through the device.

Figure 3 is a section on line 3—3 of Figure 2.

In these views, A indicates a casing having the nipples 1 thereon for receiving the hose 2 which connects the casing with the radiator and with the return pipe 3 which conveys the water from the jacket of the motor to the top of the radiator. This casing is formed of two halves, each half being indicated at 4, the two halves being fastened together by the bolts 5 which pass through holes formed in the flanges 6 on the abutting ends of the halves. A gasket 7 is placed between the flanges as shown, to make a watertight joint.

Each half flares outwardly toward the other half so as to provide a chamber larger at the center than at its ends and a cup-shaped screening medium 8 is placed in said

chamber with its open-end receiving the water from the pipe 3 so that this water will pass through the sides and closed end of the medium into the chamber and will pass from the chamber through the nipple 1 and hose 2 into the radiator. The screening medium is formed of a wire frame 9 having its sides and one end covered with wire mesh 10. Projections 11 extend from the front end of the frame and abut the front end of the casing and these projections act as spacing means for holding the front end of the screening medium away from the front end of the casing and they also help to hold the screening medium in place in the casing with its rear end bearing against the rear end of the casing with the rear edges bearing against the rear portions of the flaring walls of the rear half of the casing.

From the foregoing it will be seen that all the water passing from the water jacket to the radiator must pass through the cup-shaped screening medium so that foreign matter in the water will be caught by said medium and prevented from passing into the radiator. When the screening medium becomes clogged, it is simply necessary to remove the bolts 5 and separate the two halves of the casing and remove the screening medium to clean the same.

As before stated, this device will prevent clogging of the radiator by foreign matter contained in the water and which usually consists of rust and the like picked up as the water circulates through the jacket of the motor.

It is thought from the foregoing description that the advantages and novel features of my invention will be readily apparent.

It is to be understood that I may make changes in the construction and in the combination and arrangement of the several parts, provided that such changes fall within the scope of the appended claim.

What I claim is:

In a pipe line, a casing formed in sections, the sections having outwardly flaring side portions and flat ends, means for removably connecting the sections together, a cup-shaped screening medium placed in the cas-

ing with its open end fitting against the flat end of one section which forms the rear end of the casing, said screening medium comprising a frame formed of wire and having its sides and front end covered with wire mesh, some of the wires being spaced around the side and extending through the closed end of the medium and resting freely but tightly against the flat end of the front section, with the open end of the medium held in position by the flaring wall of the rear section.
